Filed Nov. 8, 1957, Ser. No. 695,267

3 Claims. (Cl. 23—273)

This invention relates to a method and apparatus for producing crystals having a hardness, on the Mohs' scale, equal to diamond, i.e., 10 to 10.6 on said scale.

Synthesis of diamond crystals have been attempted and, although the avenues of approach are few since methods used in connection with the synthetic production of lesser hard crystals, corundum, for instance, some attempts have been made to produce crystals of carbon by using a mixture of hydrocarbons and metallic lithium in an enclosed iron chamber, by creating high pressures resulting from the sudden cooling and the resulting rapid contraction of a mass of dissolved carbon in molten iron, and in other analogous ways. All either failed completely to produce hard crystalline carbon or, at enormous expense, produced microscopic crystals having little or no intrinsic value.

The present method approaches the problem of synthesis of diamond-hard carbon crystals by causing molten carbon to separate by precipitation out of solution with either silver or iron, the two metals that are solvents of carbon. Accordingly, it is an object of this invention to provide a method for producing carbon by precipitation, as above indicated.

Another object of the invention is to employ centrifugal force to effect such precipitation, the force being effective in all directions rather than being uni-planar. 40 A corollary object is to provide novel apparatus to produce such centrifugal force so that the precipitation of the carbon can be effected by centrifugal force in an infinite number of directions.

Another object of the invention is to precipitate carbon as above indicated, in the presence of high heat and while enclosed in a restricted crucible cavity, the invention contemplating provision of such heat during universal centrifuging as above.

The foregoing and other objects, features and advantages of the invention will be more fully realized as the following description of preferred steps of the method and of preferred apparatus for carrying out the method progresses, the same having basis on the accompanying drawings, in which:

Fig. 1 is a front elevational view of a centrifuge for carrying out the contemplated precipitation and crystallizing of carbon.

Fig. 2 is a top plan view thereof in a different position.

Fig. 3 is an enlarged fragmentary longitudinal view of a crucible used in the centrifuge.

Fig. 4 is a cross-sectional view as taken on line 4—4 of Fig. 3.

In practice, a mechanical mix comprising 90% carbon and 10% silver by volume, both in powdered form, is placed in a relatively small chamber and subjected to both heat and centrifugal force. The carbon content may vary and may be as high as 95% and as low as 50%, the hardness of the resultant crystal would vary accordingly, being harder when the proportion of carbon is higher.

The chamber is preferably substantially filled with

these two ingredients and the same is subjected to heat which is preferred to be at 3500° F. and may vary between 2300° F. minimum and 5000° F. maximum.

After the heat has been applied for a time sufficient to liquefy both ingredients, the same are subjected to the pressure generated by centrifugal force as applied by the apparatus herein disclosed.

The speed of the apparatus will, of course, depend on its size and the force achieved on the mass being centrifuged, 3000 r.p.m. is deemed to provide the force desired in apparatus of the type illustrated.

While silver is preferred as the metal, in solution, from which the carbon is precipitated, iron may be used. The present method separates or precipitates carbon from solution in silver or iron by the simultaneous application of heat and centrifugal force and, thereby crystallizing the carbon in the process.

The silver being the heavier, the same will separate from the carbon and line the chamber walls, the carbon, being confined to the center of said chamber, crystallizes under the force imposed thereon.

Referring now to the drawings, the apparatus there illustrated comprises, generally a support 5, an outer gimbal ring 6 mounted to rotate in said support on one axis, means 7 to drive the ring 6, an inner gimbal ring 8 mounted to rotate on a transverse axis in said ring 6, means 9 to drive ring 8, a crucible 10 carried by the inner gimbal ring, means 11 to heat said crucible, and means 12 to bring electric current to the means 9 and 11.

30 The support 5 is shown as a pair of bearings 15 that are arranged in alignment as shown and, while shown as separated, may be made as part of a base frame. In any case, said bearings are spaced to accommodate the outer gimbal ring 6.

Said outer ring is shown with aligned oppositely directed trunnions 16 that are disposed in bearings 15 and are provided with thrust bearings 17, arranged in opposition, to center the ring between said bearings. The outer ring is shown as of rectangular form and may have the desired mass to provide forces of inertia during rotation around the axis of trunnions 16.

The drive means 7 is shown as an electric motor 18 and a drive connection 19 between said motor and one trunnion 16 which may be extended for the purpose. A belt and pulley drive connection is shown although, a chain drive, etc. may be used.

The inner gimbal ring 8 is shown with aligned trunnions 20 disposed in bearings 21 provided in ring 6, the axis of trunnions 20 being normal to the axis of trunnions 16 of the outer ring. Thrust bearings 22, arranged in opposition, center ring 8 between its bearings.

The drive 9 is shown as an electric motor 23 carried by ring 6 and a gearing connection 24 between said motor and one of the trunnions 20.

55 The crucible 10 preferably comprises a solidly massive and elongated body comprising two separate parts 25 and 26, each provided with half of a spherical cavity 27. Said parts 25 and 26 are connected by threads 28. Since the crucible is subject to high heat, the same may be 60 made of a material suitably resistant to melting or disintegration under the heat used. One alloy suggested for this purpose is ferrozirconium. In practice, the crucible is removably mounted in ring 8, as shown, such mounting comprising end caps 29 of heat insulating material, threaded studs 30 on said caps, and threaded bearings 31 in diametrically opposite parts of ring 8 and receptive of said studs. Set screws 32 may be used to lock the studs after adjustment of caps 29 to crucible-holding position, as in Fig. 1.

70 The means 11 may preferably be of the electrical induction type and the same is here represented as a coil

33 surrounding the portion of the crucible in which the chamber or cavity 27 is provided.

It is evident that current can be brought to motor 9 and coil 33 in usual ways. Means 12, for example, shows a system of slip ring means 34 and 35 to bring current from any fixed outer part, such as one bearing 15, first to the outer ring 6, and then, from the latter, to the inner ring 8 and the means 11. While the wires or conductors, in the main, have been omitted, the manner of their provision should be clear.

Also, instrumentation, not forming part of this invention, may be used. Thus, vibration dampers may be incorporated in the device; a speed indicator, such as a tachometer, may measure the speed of one or both rings, etc.

Since variations of the invention may well be made, I desire to reserve to myself all modifications thereof that may fall within the spirit and scope of the appended claims.

Having thus described my invention, what I claim as new and desire to secure by Letters Patent is:

1. Apparatus of the character described comprising an outer gimbal ring having an axis of rotation, an inner gimbal ring on an axis of rotation transverse to the axis of rotation of the outer ring and carried by the latter, a sealed crucible carried by the inner ring and subject to the compound movement of rotation of said inner ring, and electrical heating means to heat the crucible, and means to drive each ring independently of the other, said driving means including a driving member carried by the outer ring and having driving engagement with the inner ring.

2. A centrifuging device comprising outer and inner gimbal rings on two respectively transverse axes, means to rotate each ring around its axis, the inner ring being

5 carried by the outer ring and subject to the centrifugal force imparted thereto by rotation of both rings and completely closed crucible removably carried by said inner ring, the means to rotate one ring being independent of the means to rotate the other ring.

3. A centrifuging device comprising outer and inner gimbal rings on two respectively transverse axes, electrically powered means to rotate each ring independently of the other, around its own axis, the inner ring being 10 rotatably carried by the outer ring, a completely sealed, removable crucible carried by the inner ring and subject to the centrifugal forces imparted thereto by rotation of both rings, the means for rotating the inner ring comprising an electric motor carried by the outer ring, power transmission means operatively connecting said electric motor to a trunnion of the inner ring to rotate said inner ring relative to said outer ring, slip ring means to conduct electric current to the means for rotating the inner ring, said latter means being provided between the outer and inner rings and an electrical heater coil embracing said crucible.
